(57) **CLAIM**

The ornamental design for “plunger,” as shown and described.

DESCRIPTION

FIG. 1 is a perspective view showing a first embodiment of a “plunger” incorporating the design;

FIG. 2 is a side view thereof;

FIG. 3 is a side view at 180° thereof;

FIG. 4 is a side view at 90° thereof;

FIG. 5 is a side view at 270° thereof;

FIG. 6 is a top view thereof;

FIG. 7 is a bottom view thereof;

FIG. 8 is a perspective view showing the plunger shown in FIG. 1 but fitted in a container for illustrative purposes only;

FIG. 9 is a perspective view showing a second embodiment of a “plunger” incorporating the design;

FIG. 10 is a side view of the plunger shown in FIG. 9;

FIG. 11 is a side view at 180° thereof;

FIG. 12 is a side view at 90° thereof;

FIG. 13 is a side view at 270° thereof;

FIG. 14 is a top view of the plunger shown in FIG. 9;

FIG. 15 is a bottom view of the plunger shown in FIG. 9; and,

FIG. 16 is a perspective view showing the plunger shown in FIG. 9 but fitted in a container for illustrative purpose only.
